UNITED STATES PATENT OFFICE.

HENRY H. STROMBERG, OF CHICAGO, ILLINOIS.

PHONOGRAPHIC REPRODUCER.

1,378,144.

Specification of Letters Patent. Patented May 17, 1921.

Application filed March 29, 1920. Serial No. 369,476.

To all whom it may concern:

Be it known that I, HENRY H. STROMBERG, a citizen of the United States, residing at Chicago, in the county of Cook and State of Illinois, have invented a certain new and useful Improvement in Phonographic Reproducers, of which the following is a full, clear, concise, and exact description, reference being had to the accompanying drawings, forming a part of this specification.

My invention relates to improvements in phonographic reproducers and more particularly to devices of this kind which are used with phonographs using needles which must be renewed frequently.

The principal object of my invention resides in the provision of a phonographic reproducer of the class described which carries in its casing a needle magazine for storing a quantity of reproducer needles.

A further object of the invention consists in providing mechanism in connection with the needle magazine whereby an ample supply of reproducer needles may be stored in the magazine at one loading and whereby the needles are available for use, one at a time, as occasion demands.

Another object resides in the provision of a bracket to be used in connection with my improved reproducer whereby the operation of discharging used needles and affixing new needles is greatly facilitated.

A further feature of my invention resides in the improved constructions and arrangements illustrated whereby a light compact, durable and smoothly operating device of this kind is provided which may be easily and economically manufactured.

These and other objects, advantages and uses of my improved reproducer will definitely appear in the following detailed description in which reference is made to the accompanying drawings, wherein—

Figure 1 is a top plan of a portion of the inside of a phonograph cabinet showing a turn-table and a tone arm in connection with which the improved reproducer and bracket of my invention is illustrated.

Figs. 2 and 3 are side and front elevations respectively of the improved reproducer of my invention shown in its co-operating relation to the bracket.

Fig. 4 is a side elevation of the repro-

ducer illustrated in the position in which it is preferably disposed when reproducer needles are being loaded therein.

Fig. 5 is an enlarged vertical cross-section through my improved reproducer.

Fig. 6 is a vertical section taken on line 6—6 of Fig. 5 looking in the direction indicated by the arrows.

Fig. 7 is a fragmentary enlarged-sectional detail of the reproducer casing and needle magazine, illustrating a means which I provide in the casing whereby the sharpened points of the reproducer needles are insured against damage while they are stored in the magazine.

Fig. 8 is an isolated side elevation of the magazine disk forming a part of the improved reproducer of my invention, and

Fig. 9 is an isolated side elevation of the index plate forming a part of the improved reproducer of my invention.

The same characters of reference refer to like parts throughout the views.

Referring to the drawings;

In Fig. 1, reference numeral 10 designates a phonograph casing or framework which carries a motor board (not shown) on the under side of which is mounted the mechanism for rotating the turn-table 11. The turn-table 11 is arranged to carry the usual form of disk record. At 12 is illustrated a tone arm or taper tube which extends downwardly and is pivotally supported at 13 to swing in an arc in a horizontal plane. The tone arm communicates with a horn or sound chamber in the usual manner. Pivoted to the free end of the tone arm is a goose neck or crook 14 which has the usual pin and bayonet slot connection with the sound box or reproducer of my invention which is indicated generally by the reference numeral 15.

The mechanism thus far described is entirely conventional and I claim no invention therein excepting in so far as the combination thereof with my improved reproducer is concerned. It will, of course, be understood that although I have shown a phonograph of the type utilizing a goose neck pivoted to the end of the tone arm, I do not in any wise limit the application of my invention to this specific form as will hereinafter be understood.

The improved reproducer of my inven-

tion is illustrated in sectional and elevational detail in Figs. 5 to 9 inclusive. It comprises a casing 16 in which is mounted a diaphragm 17 of mica, or any other similar transparent substance. Rubber rings or gaskets of conventional form are shown at 18 between which the diaphragm 17 is held at its edges. Secured to the diaphragm at its geometrical center is a stylus lever 19 which is pivoted in the usual manner through the studs and adjusting nut mechanism, indicated generally by the reference numeral 20. A stylus holder 21 has a bore 22 to receive a stylus or reproducer needle, one of which is shown at 23. The usual screw 24 is provided to secure the needle 23 in playing position in a well known manner.

The arrangement of parts in the reproducer proper which I have thus far described, is, of course, of conventional design and may be varied between wide limits as may be found necessary or desirable. It will, of course, be understood that vibrations imparted to the stylus or needle 23 by a record causes corresponding amplified vibration of the diaphragm 17 in the usual manner.

An index plate 25 in the form of a ring 30 snugly fits inside of the housing 16 abutting the inner gasket 18. As most clearly appears in Figs. 2, 4, 5, and 9, the plate 25 is provided with indicia which are visible through the diaphragm 17 from the side of the reproducer. The function of these indicia will presently appear.

A circular plate 26 covers that side of the housing 16 opposite the diaphragm 17. The plate 26 is apertured as shown, and a suitable boss provided thereon in which a pin 27 is secured which engages in the bayonet slot provided in the goose neck 14 to hold the sound box or reproducer 15 thereon, as aforesaid.

45 The plate 26 is secured to the housing 16 by screws, one of which is shown at 28, which pass through a flange provided on the plate 26. The plate 26 has an inwardly projecting cylindrical boss 29 which snugly fits the inside of the housing 16. The inner end of the boss 29 engages the index plate 25 and serves to retain the same along with the diaphragm 17 and gaskets 18 in proper operative position. The boss 29 is shouldered annularly as at 30 and 31 to receive the magazine disk 32. The magazine disk 32 has a central aperture 33 and a concentric cylindrical boss 34 on which is secured, in any suitable manner, the ratchet ring 35.

60 Provided in the disk 32 is a plurality of radially extending bores 36 which extend toward the aperture 33 from the periphery of the disk. The bores 36 are of sufficient depth and gage to receive any one of a

number of standard size reproducer needles 65 shown at 23.

Provided in the inner face of the plate 26 is a channel or groove 37 in which is movable a plate 38. Laterally projecting lugs or ears 39 and 40 are provided at opposite ends of the plate 38. A rod 41 extends through registering bores in the housing 16 and the plate 26 and has screw-threaded engagement with the lug 39. The outer end of the rod 41 is enlarged to provide a suitable key or finger piece 42. A tension spring 43 serves to hold the plate 38 normally in the position shown in Fig. 6 with the key 42 projecting freely outside of the housing 16 as shown.

80 Pivoted to the plate 38 on the pin 44 is a pawl 45, the free end of which engages in the ratchet 35 as shown in Fig. 6. A leaf spring 46 secured in lug 40 of the plate 38 functions to urge the pawl 45 normally into engagement with the ratchet 35. A stop pin 47 limits the counter-clockwise movement of the pawl 45 on the pin 44. Provided in the magazine disk 32 on the side which engages the plate 26 are depressions 48 in which a ball 49 is arranged to engage, under tension of a spring 50 which is received in a cap 51.

85 The ratchet 35, it will appear from an inspection of Fig. 8, is so proportioned with respect to the magazine disk 32, that the number of teeth therein is equal to the number of needle receiving bores 36 and depressions 48.

90 An opening 52 is provided in the casing 16 which extends from the shoulder 30 in the plate 26 through the cylindrical boss 29 thereof and through the wall of the housing 16. The opening 52 communicates with the bore 22 which is provided in the needle holder 21 as aforesaid.

95 From the foregoing description, it will appear that upon depression of the key 42, the pawl 45 rotates the magazine disk 32 in a counter-clockwise direction as viewed 100 in Fig. 6. At the limit of the inward movement of the key 42, the ball 49, under pressure of spring 50, drops into one of the depressions 48 provided in the disk 32. Upon release of the key 42, spring 43 acts to return the plate 38 to its normal position. The pawl 45 riding over a tooth of the ratchet 35, engages in the next notch preparatory to further advancement of the disk 32.

105 Provided in the shoulder 30 of the plate 26 is a comparatively deep and narrow annular groove 53. It will appear that needles arriving at or near the lower end of the housing 16 upon periodic advancement of the disk 32 will tend to drop out of the needle receiving bores 36 and the finely sharpened points thereof would ordinarily be abraded by the inner adjacent face of

the shoulder 30 of the plate 26. However, as seen in Fig. 7, the tapered end of the needles 23 engage in the groove 53, the fine sharp playing points thereof lying free from engagement with any hard substance. The groove 53 being comparatively narrow and deep will function properly as aforesaid with any standard size reproducer needle. In addition to serving in the above capacity, 10 the groove 53 acts to prevent any slight vibration or jarring of the needles 23 during the playing of a selection.

It will, of course, appear that in loading the magazine 32 with reproducer needles, 15 the reproducer 15 is preferably disposed upside down as seen in Fig. 4. A bracket 54 is generally provided on the tone arm 12 and assists materially in the loading of needles. However, where such provision has not been 20 made, finger holds 55—55 provided on the casing 16 are advantageous. A quantity of new needles may be held in the one hand or strewn on the turn-table 11. With the other hand, the operator may actuate the key 42. 25 Reproducer needles are dropped blunt end forward into the bore 22 of the needle holder 21, the screw 24 being, of course, loosened. A needle, when thus dropped, passes through 30 the opening 52 into one of the needle receiving bores 36 in the magazine disk 32. The key 42 is thereupon depressed to advance the disk 32 as above described. If the operator should unconsciously forget to depress the key 42 after having dropped a needle into 35 the bore as described, and he should attempt to drop another needle into the same bore, the needle will not be received in the bore with the other needle, because the bores are not provided of sufficient size to accommodate 40 more than one needle. It is, therefore, impossible to store two needles in one bore. The operator alternately drops a needle into 45 the needle holder 21 and depresses the key 42. This operation is repeated until all of the bores 36 have been filled. The degree of load and unload is indicated by an index mark 56 on the magazine disk 32 which is preferably disposed adjacent the mark "0" when the magazine is empty. It will, of course, be 50 apparent that any form of indicia may be provided either on the index plate 25 or disk 32 in place of the specific form described.

I shall now describe a form of bracket of my invention which is particularly adapted 55 for use with my improved reproducer. The bracket is indicated generally by the reference numeral 57 and is particularly illustrated in Figs. 1 to 3 inclusive. The bracket 57 is secured in any suitable manner to the 60 inside of the phonograph cabinet, as by screws 58—58, and its free end projects horizontally toward the turn-table 11 and preferably, lies slightly above the plane of the upper face thereof. The free end of the

bracket 57 lies directly over the mouth of a 65 receptacle for used needles shown at 59. At its free end, the bracket 57 has a slight channel 60 formed in its upper edge which receives the lower edge of the reproducer casing 16, adjoining the point 20 as shown most 70 clearly in Fig. 2. A depending arm 61 on the bracket 57 has a lug 62 provided at its free end.

After the magazine 32 has been filled with reproducer needles as above described, the 75 needles are available, one at a time, by depressing the key 42 as will be apparent. When a selection is to be played, the tone arm 12 is swung to a position such that the reproducer 15 occupies the position shown 80 in Figs. 1 to 3 inclusive. The key 42 is depressed and a needle 23 thereupon falls down out of the disk 32 through the opening 52 into the bore 22 of the needle holder into engagement with lug 62 of the bracket 57 as 85 shown in Figs. 2 and 3. The screw 24 is then tightened in the usual manner. The lug 61 is spaced at such a distance from the needle holder 21 that the needles 23, upon engaging it, protrude from the holder 21, a 90 distance which practice has shown to be most desirable from the standpoint of good reproduction. The lug 61, therefore, acts not only as a spacing means, as described, but also as a stop to prevent the needles from falling into the phonograph cabinet when they are dropped from the magazine as aforesaid. After the selection is played, it is necessary 95 to renew the reproducer needle before repeating the selection. The reproducer 15 is then moved to a position on the bracket 57, such that the reproducer needle does not engage the lug 61, but extends to the right 100 thereof. (See Fig. 3.) The screw 24 is then loosened and the needle 23 drops into the receptacle 59 which is provided for the reception of such used needles. 105

While I have described my invention as applied to phonograph reproducers, it will, of course, appear that certain of the above 110 described improvements may be used to advantage in phonographic recorders, as well, without departing from the spirit of my invention.

While my improved reproducer may be 115 made in various ways, and while any suitable material may be used in the manufacture thereof, I prefer to make such parts as the casing 16, plate 26 and disk 32 by a die-casting process, using any one of the various 120 metal compounds used in this process. By so manufacturing my reproducer, I have found that the same may be made very economically and is, when completely assembled, very light and durable. 125

Having thus described my invention, what I claim as new and desire to secure by Letters Patent of the United States, is:

1. In a phonographic reproducer comprising a casing and a needle holder therefor, the combination with a disk in said casing arranged to receive a supply of needles, of 5 an annular groove in said casing arranged to receive the pointed ends of said needles to protect them from abrasion.
2. In a phonographic reproducer comprising a casing, the combination with a needle 10 holder of a magazine in said casing for storing a quantity of needles in radial relation over said needle holder, and means to intermittently rotate said magazine to cause needles to drop into said holder one at a 15 time.
3. In a phonographic reproducer comprising a casing, the combination with a needle holder of a disk in said casing, said disk having needle-receiving bores extending inwardly from the periphery thereof, and means for rotating said disk.
4. In combination with a phonographic reproducer comprising a casing and a needle holder therefor, a disk in said casing, said 25 disk comprising needle-receiving means, and means releasing needles from said disk to drop into said needle holder.
5. In combination with a phonographic reproducer comprising a casing and a needle 30 holder therefor, a needle magazine in said casing for storing needles therein, and means for releasing needles from said magazine to be used in said holder.
6. The combination with a phonographic 35 reproducer comprising a casing and a needle holder therefor, a magazine in said casing, said magazine comprising needle-receiving means, means for releasing needles from said magazine to be used in said holder, and 40 means for indicating the degree of load and unload of said magazine.
7. In a phonographic reproducer comprising a casing, a needle holder, a transparent 45 diaphragm in said casing, an index plate therebehind, said plate comprising indicia, a disk in said casing in back of said plate arranged to store needles, said disk having an index mark thereon, and means for rotating said disk.
- 50 8. A phonographic reproducer comprising a casing, a transparent reproducer diaphragm therein, a needle holder, a stylus lever joining said needle holder and diaphragm, a needle magazine disk in said casing in back of said diaphragm over said needle holder, said disk having radially extending bores therein adapted to receive reproducer needles, said casing having an opening 55 affording communication between said needle receiving bores and said needle holder, an annular groove in said casing extending around the periphery of said disk adapted to receive the pointed ends of the reproducer needles to prevent abrasion

thereof, means for imparting rotary movement to said needle magazine disk comprising a ratchet on said disk, a spring-pressed pawl engaging said ratchet, a finger-piece connected therewith adapted, when depressed, to actuate said pawl to rotate said disk whereby needles may drop from the bores in said disk through the opening in said casing into said needle holder, an index mark on said disk, an index plate in front of said disk, said plate bearing indicia relative to the number of needles which said magazine is capable of holding, said disk, when rotated, causing movement of said mark whereby the degree of load or unload of the magazine is indicated, and detent mechanism for yieldingly holding said needle magazine disk in its adjusted position comprising a spring-pressed ball, and depressions in one face of said needle magazine disk adapted to receive 85 said ball.

9. A phonographic reproducer, comprising a casing, a reproducer diaphragm therein, a needle holder, a stylus lever joining said needle holder and diaphragm, a needle magazine disk in said casing, said disk having bores therein adapted to receive reproducer needles, means for imparting rotary movement to said disk, comprising a ratchet on said disk, a pawl engaging said ratchet, 90 a finger-piece connected therewith adapted, when depressed, to actuate said pawl to rotate said disk, whereby needles may be released from the bores in said disk to be used in said needle holder and detent mechanism 95 for holding said needle magazine disk in its adjusted position comprising a ball adapted to be received in depressions formed in one face of said needle magazine disk.

10. A phonographic reproducer, comprising a casing, a transparent reproducer diaphragm therein, a needle holder, a stylus lever joining said needle holder and diaphragm, a needle magazine disk in said casing, said disk having bores therein adapted 110 to receive reproducer needles, means for imparting rotary movement to said disk, comprising a ratchet on said disk, a pawl engaging said ratchet, a finger-piece connected therewith adapted, when depressed, to actuate said pawl to rotate said disk, whereby needles may be released from the bores in said disk to be used in said needle holder, an index mark on said disk, an index plate between said disk and said diaphragm, said disk, when rotated, causing movement of said mark, whereby the degree of load or 115 unload of the needle magazine is indicated.

11. A phonographic reproducer comprising a casing, a transparent reproducer diaphragm therein, a needle holder, a stylus lever joining said needle holder and diaphragm, a needle magazine in said casing, 125

said magazine being adapted to receive reproducer needles, means for actuating said magazine to release needles therefrom to be used in said needle holder, an index mark 5 on said magazine, an index plate having indicia relative to the number of needles which said magazine is capable of holding, said magazine, when moved, causing movement of said index mark whereby the degree 10 of load or unload of the magazine is indicated.

12. A phonograph reproducer comprising a casing, a diaphragm therein, a needle holder, a stylus lever joining said needle 15 holder and diaphragm, a needle magazine in said casing, having bores therein for receiving reproducer needles, a groove in said casing adapted to receive the pointed ends of the reproducer needles to prevent abrasion 20 thereof and means for actuating said needle magazine to release needles therefrom to be used in said needle holder.

13. The combination in a phonograph comprising a casing, a turn table, a tone arm 25 mounted in said casing adjacent said turn-table and a receptacle for used needles at one side of said turn-table adapted, when said tone arm is in an operative position to lie beneath the free end thereof, of a reproducer 30 on said tone arm, said reproducer comprising a needle magazine for storing a quantity of reproducer needles, said magazine adapted when actuated to dispense needles, one at a time, for use in the reproducer, and a 35 bracket in said casing over said used needle receptacle adapted to support said repro-

ducer in inoperative position whereby used needles released from said reproducer may drop into said receptacle, the said bracket comprising an abutment adapted, when said 40 reproducer is supported on said bracket, to lie in spaced relation thereto, a distance equal to that which the reproducer needles must protrude from the reproducer to effect proper reproduction of sound, said abutment being adapted to stop and gage the needles as the same are dispensed, one at a time, by said needle magazine.

14. The combination in a phonograph comprising a casing, and a tone arm mounted in said casing, of a reproducer on said tone arm, said reproducer comprising a needle magazine adapted when actuated, to dispense needles, one at a time, for use in the reproducer and a bracket in said casing 50 adapted to support said reproducer in inoperative position, said bracket comprising an abutment adapted when said reproducer is supported on said bracket, to lie in spaced relation thereto a distance equal to that 55 which reproducer needles must protrude from the reproducer to effect proper sound reproduction, said abutment being adapted to stop and gage the reproducer needles as the same are dispensed one at a time by said 60 needle magazine.

In witness whereof, I hereunto subscribe my name this 26th day of March, 1920.

HENRY H. STROMBERG.
